CLAIM

The ornamental design for an electronic gaming machine, as shown and described.

DESCRIPTION

This application is related to U.S. patent application Ser. No. 16/224,661, entitled “Gaming Machine Display Having One or More Curved Edges” and filed on Dec. 18, 2018, which is hereby incorporated by reference and for all purposes. FIG. 1 is a front isometric view of an electronic gaming machine.

FIG. 2 is a front view thereof.

FIG. 3 is a side view thereof.

FIG. 4 is an opposing side view (as compared to FIG. 3) thereof.

FIG. 5 is a top view thereof.

FIG. 6 is a rear view thereof; and,

FIG. 7 is a bottom view thereof.

The dash-dot-dash lines seen in FIGS. 1, 2, and 5 indicate tangent edges. The broken lines shown in the drawings depict portions of the electronic gaming machine that form no part of the claimed design.
